UNITED STATES PATENT OFFICE

LOUIS BOBBIN, ABRAM SIMON AND NATHAN BENDERSON, OF TROY, NEW YORK

BAKING OVEN

Application filed December 20, 1930. Serial No. 503,848.

This invention relates to an improvement in baking ovens, and more specifically to that type of large bakers' ovens which necessitate a supply of steam during the course of baking.

It is an object of our invention to provide a novel form of steam generator, which is of simple but rugged construction. This novel steam generator is characterized by a low initial cost of installation as well as by remarkably low costs of maintenance and operation.

Another object of our invention is to provide for a reliable indication of the thermal conditions of the oven.

Another object of our invention is to provide an effective heat equalizer for the oven.

It is another object of our invention to provide a single element, which may be easily adapted to any type of bake oven, of either forced or natural draft, and which is capable of performing the functions of a steam generator, thermal indicator, and heat equalizer. This unit is as easily adapted to be disposed in a previously constructed oven as in one newly built.

The nature and advantages of our invention will be better understood in the light of the following description of a preferred embodiment thereof, when considered in connection with the accompanying drawings, wherein like reference numerals indicate similar parts in the several views:

Fig. 1 is a front elevation of the bake oven which embodies our invention.

Fig. 2 is a perspective view of the interior of a bake oven illustrated in Fig. 1, but with a right hand fire compartment, instead of a left hand one as indicated in Fig. 1.

Fig. 3 is a detailed view of the element which constitutes the essence of our invention.

Figs. 4 and 5 are sectional views of Fig. 3 along line 4-4 and 5-5 respectively.

In the drawings, 1 represents the front wall of a conventional bakers' oven. 2 represents the firing gate. The baking compartment is closed by gate 3, which may be of the pivoted type, as illustrated, or else of the vertically moving type, which is well

known in this art. The coal pocket 4 is provided for a convenient storage of fuel. Blower fan 5 is designed to give a forced draft through the chamber communicating with the grate 6. Gate 7 allows the periodic removal of the ashes. Pyrometer 8 is exposed to view at a convenient height for viewing the indication of the heat conditions in the interior of the oven.

The principal feature of the invention is illustrated in Fig. 2, and in more detailed forms in Figs. 3-5, by element 10, with the wing portion 11 integral therewith. This unit serves as an effective guard member between the baking compartment 12 and the fire compartment above and surrounding the grate 6. We preferably cast this member of a metal, which gives thereto a high heat resistance. We have found a semi-steel alloy with a substantial proportion of manganese therein, particularly suited for our purposes, since such an alloy has proved not to buckle under service and not to scale overmuch. This member is off-set from the grate in order that it may not be exposed directly to the forced draft and reach an undesired red heat.

It is the object of our invention to generate steam in the oven by spraying a jet of water upon this member at periodic intervals, the frequency of which is determined by operating conditions. Our invention contemplates a spraying tube 30, suitably mounted adjacent the guard member adapted to be continually or intermittently operated, in the interior of the oven. Also,

as shown, a source of water may conveniently be led to a flexible tube and nozzle attachment 15 adjacent the baking chamber gate. The gate 3 is opened and the spray is directed against the edge 13 of the steam generator. Suitable baffle plates, if found necessary surround the gate opening to prevent the steam from issuing from the oven at that point. The member 10 is formed with a ledge 14, which together with edge 13, forms a gutter or spout for the retention of the water that is not immediately evaporated. We have found such a spout particularly necessary at the corner 16, at which point the water has a tendency to accumulate. For that reason,

we have designed the ledge portion at that point to be of a greater height, in order to more effectively retain the water that does not evaporate immediately. To insure that
5 the water shall not overflow the ledge at this point, and do possible damage to the bread in the baking compartment, we have provided overflow apertures 18 which may be of any desired shape and number, in order that
10 the water shall lead to the burning coals, where steam is generated thereby, without any harmful results.

The extremity of wing portion 11 is of slightly increased height than the rest of it.
15 By virtue of this feature we obtain a larger abutting edge of this element against the edge of the furnace, thereby rendering the same more stable, as well as preventing the coals that accumulate at that corner from falling
20 over to the baking compartment. Although we have shown portion 11 disposed at an obtuse angle relative to portion 10, we do not wish to be limited to such, since the construction of the oven will serve to determine
25 the nature of these structural features.

Our device for generating steam offers many advantages over the characteristic structures of the prior art for that function. We have eliminated the steam boiler and
30 steam pipes with the attendant great costs of operation. Necessary shut-downs for steam pipe and boiler repairs are eliminated. No special attention need be given our steam generator. In fact it serves as an effective "set-
35 ter" or heat equalizer, since its mass makes possible an efficient storage of heat between baking operations. Thus the most economical use of the fuel is availed of since very little, if any, of the heat is wasted after the
40 same is used for both the heating of the baking compartment and for the generation of the steam.

Element 10 lends itself to the efficient performance of another function. In ovens of
45 the prior art it has been difficult to obtain a reliable thermal indication of the condition of the oven because of so called "cold pockets" and eddy currents. In the interior of element 10, we provide a recess 19 for the
50 insertion of a heat responsive element, which may be of the thermocouple type, or else of the bimetallic type, and lead the same through a conduit 9, to the indicating instrument 8 on the exterior of the oven. The interior of element 10 does not fluctuate in its heat content. Thus a record of the heat at that point is a reliable one and truly indicative of the actual thermal condition of the
55 oven. Aperture 19 may be sealed if desired.

It will be seen that we have provided a simple and effective expedient in the bake oven art. While we have described our invention as embodied in a concrete form, it
60 should be understood that our invention is

not limited thereto, as various modifications thereof will suggest themselves to those skilled in the art, without departing from the spirit of our invention, the scope of which is set forth in the annexed claims.

70

What we claim is:

1. In combination with a baking oven, a baking compartment, a fire compartment, a guard member disposed between said compartments comprising a heavy metal casting, an aperture extending into the interior of said casting and a thermal responsive element disposed in said aperture.

75

2. In combination with a baking oven, a baking compartment, a fire compartment, a guard member disposed between said compartments comprising a heavy metal casting and an integral wing portion disposed angularly thereto, means for spraying water upon the edge of said heavy metal casting facing said baking compartment for the generation of steam in said oven, and a spout in the lower portion of the edge of the metal casting facing said baking compartment for the retention of non-evaporated water.

80

3. In combination with a baking oven, a baking compartment, a fire compartment, a guard member disposed between said compartments comprising a heavy metal casting and a wing portion disposed angularly thereto, means for spraying water upon the edge of said heavy metal casting for the generation of steam in said oven, a spout in the lower portion of the edge of the metal casting for the retention of non-evaporated water, said spout being deeper at the point of jointure of the wing portion and the heavy casting, and apertures communicating from said deeper portion of said spout to said fire compartment.

85

4. In combination with a baking oven, a baking compartment, a fire compartment, a metallic guard member disposed between said compartments, one portion of said guard member being formed of a mass of metal of substantial thickness, a wing plate integral with said first-mentioned portion extending in a plane substantially perpendicular to the floors of said compartments, and means for spraying water upon the edge of said guard member facing said baking compartment for the generation of steam in said oven.

100

5. In combination with a baking oven, a baking compartment, a fire compartment, a metallic guard member disposed between said compartments, one portion of said guard member being formed of a mass of metal of substantial thickness, a wing plate integral with said first-mentioned portion extending in a plane substantially perpendicular to the floors of said compartments, and an apertured water tube adjacent said first-mentioned portion upon the side thereof facing said baking compartment for directing
